UNITED STATES PATENT OFFICE.

JOSEPH E. LEONARD AND GEORGE H. ILTEN, OF CEDAR RAPIDS, IOWA.

STOVE AND RANGE.

1,171,731.

Specification of Letters Patent.

Patented Feb. 15, 1916.

Application filed February 27, 1915. Serial No. 11,096.

To all whom it may concern:

Be it known that we, JOSEPH E. LEONARD and GEORGE H. ILTEN, citizens of the United States, residing at Cedar Rapids, in the county of Linn and State of Iowa, have invented certain new and useful Improvements in Stoves and Ranges; and we do hereby declare the following to be a full, clear, and exact description of the invention, such as will enable others skilled in the art to which it appertains to make and use the same.

This invention relates to stoves and ranges, and more particularly that type of range in which the oven is elevated some distance above the combustion chamber, and gets its heat from the combustion chamber through a flue connecting said chamber with the bottom of the oven.

The object of this invention is to provide for the heating of the oven by gas, when desired, independently of the regular combustion chamber.

The nature of the invention is fully disclosed in the description and claims following, reference being had to the accompanying drawings, in which—

Figure 1 is a front view of a device embodying our invention. Fig. 2 is a central section of the same. Fig. 3 is a section of the same transverse to Fig. 2, showing also the application of the device to a high oven. Fig. 4 is a view from the under side, of the gas-burner detached.

Referring to Fig. 3, which shows in section an oven and connected parts of a high-oven range, the numeral 1 designates the part of the combustion chamber communicating directly with the oven through a vertical flue 2. This flue at its upper end connects with the bottom of the oven 3, the products of combustion passing up and around the interior of the oven (the oven proper) and out through the smoke-pipe connection 4, as indicated by the arrows. As usually constructed the connection of the flue 2 with the bottom of the oven is direct, but as herein illustrated the gas-burning apparatus serves as a collar to connect said parts, as will more fully hereinafter appear.

In the present embodiment of the invention, which represents the preferred construction, the gas-burner 5 is in the form of an oval ring, suitably pierced at 6 for the escape of the burning gas. At each end of the oval is a hub 7 tapped for connection with a gas-pipe 8 at either end as conven-

ience may require, the other end being suitably plugged at 9, as shown. From the upper side of the hollow ring extends a flange 10 adapted to be bolted to the bottom of the oven. The section of pipe 8 serves also for the admission of air, its expanded end 11 having an adjustable gate 12 for the regulation of the air supply. Into this enters the gas-jet 13, provided with a suitable cock 14.

Instead of connecting the flue 2 with a flange at the bottom of the gas ring, as might be done, it is preferred in practice to connect the ring with a separate collar 15, which fits inside the flue in the usual way, and has an internal seat 16 to receive an annular flange 17 formed at the bottom side of the ring. The parts are connected by bolts 18 passing through the respective parts, as shown.

The location of the gas outlets of the burner is not of the utmost importance, but in practice it is preferred to place them below the ring, as shown. This does not interfere with the heating action of the burner, while the position of the holes is such as to protect them from obstruction by falling soot, or the like.

The device is of special value in connection with ranges using wood or coal as their ordinary fuel. These are often installed, however, in houses, provided with a gas supply. In such cases it becomes possible, by means of this device, to use a part of the heating apparatus, the oven as herein shown for baking, or the like culinary operations that do not require the regular combustion chamber, without the trouble of building a fire in such combustion chamber. The form of the gas-burner may of course vary considerably from that shown, without departing from the gist of the invention, but the type illustrated is the construction preferred in practice, since it is very efficient for gas, and offers no obstruction to the products of combustion from the regular combustion chamber, when the gas is shut off.

Though not of primary importance, it is to be noted that the gas-burner is useful also as a means for keeping the heat passages of the oven clear of soot, the independent use of the gas burner tending to burn out unconsumed carbon accumulating in such passages.

Air to support the combustion of gas might be supplied from the combustion chamber through suitable air passages there-

in, but in practice it is preferred to provide the gas-burner with an air supply independent of the other parts of the stove, and in close proximity to the burner. This is done by forming the collar 15 with air passages 19, which may be closed by a door 20 when the gas burner is not in use. The door is preferably mounted on an inclined door or damper support 21 attached to the front of said collar, and inclosing the openings therein. The opening affords a convenient means for lighting the gas, and supplies an abundance of air for combustion.

Having thus described our invention, we claim:

1. In a stove or range having a combustion-chamber, an oven served thereby and a connecting flue, a gas-burner conforming to the cross-sectional contour of said flue, and forming a connecting collar between the flue and the oven, presenting no interior ob-

struction to the passage of the products of combustion from the range, said collar being recessed interiorly, with gas-outlets within said recess and opening downwardly, whereby said outlets are protected from falling soot, substantially as described.

2. In a stove or range having a combustion chamber, an elevated oven served thereby, and a connecting flue for the products of combustion, an annular gas-burner flanged for connection with the bottom of the oven, a collar connected with the upper end of the flue, and a connection of said burner and collar, substantially as described.

In testimony whereof we affix our signatures in presence of two witnesses.

JOSEPH E. LEONARD,
GEORGE H. ILTEN.
